UNITED STATES PATENT OFFICE.

CHARLES RUST, OF YONKERS, NEW YORK.

PAINTING APPARATUS.

1,217,071.

Specification of Letters Patent. Patented Feb. 20, 1917.

Application filed April 29, 1916. Serial No. 94,414.

To all whom it may concern:

Be it known that I, CHARLES RUST, a citizen of the United States, residing at Yonkers, in the county of Westchester and State 5 of New York, have invented certain new and useful Improvements in Painting Apparatus, of which the following is a specification.

My invention relates to improvements in painting apparatus which while specially 10 constructed for use in painting hollow metal beds, may be used for any purpose where it would operate in an efficient manner.

At present in the painting of hollow metal beds by the dipping or immersion process, 15 the paint enters the interior of the hollow bed sections and in this manner a great amount of paint is wasted. The main purpose of my invention is the provision of an apparatus which will overcome this objection and will prove a great saving in the amount of paint used upon the beds.

Another object of my invention is the provision of an apparatus which will quickly and readily dip the head or foot section of 25 the bed and insure the proper application of the paint to the entire surface, thus performing its functions in a rapid and efficient manner.

Another object of my invention is the provision of a painting apparatus which will 30 paint the bed sections in a smooth and even manner, which will have means for raising and lowering the sections, and in conjunction with such raising and lowering means, 35 will have means for conveying the painted bed sections to any desired place.

A further object of my invention is the provision of a painting apparatus which will 40 operate with ease and rapidity, which will be of simple, durable and inexpensive construction, and which generally will be thoroughly efficient and practical.

With these objects in view my invention 45 consists of means for raising and lowering the bed sections, a paint containing tank for applying the paint to said sections, and floats in said tank for fitting the open ends of the posts of said sections to prevent paint from entering the bed sections.

50 The invention further consists of means for raising and lowering the bed sections, means for applying the paint to said sections, means for closing the hollow posts to prevent the paint from entering the interior 55 of said sections, and means for receiving and conveying the painted sections.

The invention finally consists in a painting apparatus embodying novel features of construction and combination of parts for service, substantially as shown, described 60 and claimed.

In order that the details of construction and the operation of my invention may be understood and its many advantages be appreciated, I have shown in the accompanying 65 drawing an apparatus embodying my improvement, it being understood that I reserve the right to make any changes in the construction which fall within the scope of the claims.

70 Figure 1 is a side elevation of a complete painting apparatus constructed in accordance with my invention, the tank being shown in section to illustrate the float construction and the manner of dipping and 75 elevating the bed sections.

Fig. 2 is a sectional view on the line 2—2 of Fig. 1.

Fig. 3 is a sectional view on an enlarged scale of the float and portion of the bed 80 post, showing the operation of the float acting as a plug or stopper.

Fig. 4 is a sectional view of a hollow metal construction of float, and

Fig. 5 is a detail view of the track and the 85 rack traveling thereon, said rack supporting the painted sections.

Referring by letter to the drawing, in which similar letters denote the same part in all the views:—

90 The letter A, designates a tank or receptacle of the proper size and shape for containing the paint, said tank being formed with the flaring mouth B, the purpose of which is to save the paint which drops from 95 the head or foot bed sections C, said sections being raised or lowered through the medium of the frame D having the hooks E, and from which leads the flexible cord F over drum G, on shaft H, which shaft is mounted 100 in hangers J, and also carries the drum K, upon which is wound the flexible connection L, carrying the weight M, providing a counter balance means by which the bed sections are easily and quickly raised and lowered 105 into the tank containing the paint.

In the tank are secured the devices N, which form the anchoring means for the flexible connections O, to whose upper ends are secured the floats P, formed with reduced portions Q, fitting in the lower hollow ends of the posts of the bed or foot sections 110

of the bed and forming plugs or stoppers to close the open ends of the post and prevent the entrance of paint.

It will thus be seen that the bed sections are lowered into the tank and that as soon as said sections enter the tank the floats close the hollow posts and allow the paint to be applied to the exterior of the bed sections but prevent any paint from entering the interior, and that as soon as the section has been completely dipped in the paint it is raised and placed upon the rack R, which is provided with a trolley construction S, adapted to travel on a track T, for the proper distance where it is received by the turn table U, and by which it is directed to any desired place, said turn table forming a connection with tracks leading to any place desired.

From the foregoing description taken in connection with the drawings, it will be at once apparent that I provide means for applying the paint to the exterior or surface and preventing it from entering the interior of the sections, also that such means are positive and automatic in their action and that in addition to providing such means the apparatus embodies a receiving and conveying mechanism for the bed sections, all of which operate jointly to form a complete and efficient apparatus for the purposes intended.

I claim:—

1. A painting apparatus, consisting of a paint container, means for lowering hollow bed sections into said container and elevating said sections therefrom, and means in said container to prevent the entrance of paint to the interior of said bed sections.

Copies of this patent may be obtained for five cents each, by addressing the "Commissioner of Patents, Washington, D. C."

2. A painting apparatus, consisting of a paint container, means for lowering hollow bed sections into said container and elevating said sections therefrom, and buoyant means in said container to prevent the entrance of paint to the interior of said bed sections.

3. A painting apparatus, consisting of a paint container, counter balance means for lowering and raising hollow bed sections, floats in said container to act as stoppers to close the hollow posts of said bed sections, and means for anchoring said floats.

4. A painting apparatus, consisting of a paint container, means for lowering hollow bed sections into said container and elevating said sections therefrom, and floats in said container having a reduced portion adapted to fit in and close the ends of the hollow posts of said bed sections.

5. A painting apparatus, consisting of a paint container, means for lowering hollow bed sections into said container and elevating said sections therefrom, and floats in said container having a reduced portion adapted to fit in and close the ends of the hollow posts of said bed sections, said lowering and raising means consisting of a counter shaft disposed above said container, a pair of pulleys mounted thereon, and a counter balance secured to one pulley and a bed section engaging hook secured to the other, substantially as described.

In testimony whereof I affix my signature in the presence of two witnesses.

CHARLES RUST.
